US00D948568S

(12) United States Design Patent (10) Patent No.: US D948,568 S
(45) Date of Patent: * Apr. 12, 2022

(54) DISPLAY SCREEN WITH ICON(71) Applicant: Google LLC, Mountain View, CA (US)(72) Inventors: Joseph William Traylor, San Francisco, CA (US); Sang Yoon Han, Campbell, CA (US); Jun Yong Shim, San Francisco, CA (US); Stephen Anthony Hodge, Oakland, CA (US); Judy Zhao, Menlo Park, CA (US)(73) Assignee: GOOGLE LLC, Mountain View, CA (US)() Term: 15 Years(21) Appl. No.: 29/808,035(22) Filed: Sep. 16, 2021*Related U.S. Application Data

(63) Continuation of application No. 29/722,983, filed on Feb. 3, 2020, now Pat. No. Des. 933,096.

(51) LOC (13) Cl. ..... 14-04(52) U.S. Cl.USPC ..... D14/489(58) Field of Classification Search

USPC D14/485-495; D20/10, 11, 22-33, 39,

Primary Examiner — Ian F Whitmore(74) Attorney, Agent, or Firm — Plumsea Law Group, LLC(57) CLAIM

The ornamental design for a display screen with icon, as shown and described.

DESCRIPTION

The sole FIGURE is a front view of a display screen with icon, showing our new design.

The broken lines of uneven length show the display screen and form no part of the claimed design.

1 Claim, 1 Drawing Sheet(56)
